[57] CLAIM

The ornamental design for a pair of spectacles, as shown and described.

DESCRIPTION

FIG. 1 is a front elevational view of a pair of spectacles embodying my new design;

FIG. 2 is a plan view of the spectacles with a temple broken away for convenience of illustration;

FIG. 3 is an elevational view of one side of the spectacles, the opposite side thereof being of substantially the same appearance; and

FIG. 4 is a rear elevational view with the temples removed for clarity of illustration.
